(57) **CLAIM**

The ornamental design for a tooth washing instrument, as shown and described.

DESCRIPTION

FIG. 1 is a top, front perspective view of a tooth washing instrument showing my new design.

FIG. 2 is a front view of a tooth washing instrument.

FIG. 3 is a rear view of a tooth washing instrument.

FIG. 4 is a left side view of a tooth washing instrument.

FIG. 5 is a right side view of a tooth washing instrument.

FIG. 6 is a top view of a tooth washing instrument.

FIG. 7 is a bottom view of a tooth washing instrument.

FIG. 8 is a bottom, rear perspective view of a tooth washing instrument.

FIG. 9 is an enlarged view of a tooth washing instrument taken from the circle part in FIG. 2.

FIG. 10 is an enlarged view of a tooth washing instrument taken from the circle part in FIG. 3; and,

FIG. 11 is an enlarged view of a tooth washing instrument taken from the circle part in FIG. 4.

The broken lines in the drawings depict portions of the tooth washing instrument that form no part of the claimed design.
